UNITED STATES PATENT OFFICE.

CHARLES SCHWARTZ, OF BROOKLYN, NEW YORK, ASSIGNOR TO ALTHOF, BERGMANN & CO.

TOY WHISTLE.

SPECIFICATION forming part of Letters Patent No. 233,377, dated October 19, 1880.

Application filed July 9, 1880. (No model.)

To all whom it may concern:

Be it known that I, CHARLES SCHWARTZ, of Brooklyn, in the county of Kings and State of New York, have invented a new and Improved 5 Toy Whistle, of which the following is a full and exact description.

This invention relates to a new toy whistle which is combined with a fan-wheel and toy figure, so as to utilize the air blown toward the 10 whistle, revolving the wheel and the toy figure, and raising and lowering the same on an upright standard, thereby adding to the amusement which a whistle usually affords to children.

15 In the accompanying drawings, Figure 1 represents a side view, partly in section, of my improved toy whistle. Fig. 2 is an end view, partly in section, of the same; and Fig. 3, a partial top view thereof.

20 Letter A in the drawings represents a straight or other whistle or blow-pipe, through which air is blown at the mouth end a, and from which it escapes through an aperture, b, at the top. The whistle proper, c, is attached to the 25 end opposite the mouth end, and is of suitable construction; but said whistle for many purposes may be dispensed with when the instrument is to be noiseless.

To the tube A is attached an upwardly-projecting arm, d, which has a socket, e, in which an upright rod or standard, B, is held.

D is a fan-wheel fitted around the standard B, and made of pasteboard, paper, sheet metal, or other equivalent material, with wings f, so 35 arranged that said wings will be affected by the air blown through the hole b and the fan-wheel D revolved thereby. Upon said fan-wheel D is secured a toy figure, E, which also is swiveled around the standard B, and will 40 revolve around the same, together with the fan-wheel.

The figure E has pivoted arms g and other pivoted limbs, if desired.

As air is blown through the tube A the wheel D, together with the figure E, will be 45 revolved, and at the same time said wheel and said figure will ascend under the air-pressure on the standard B, and by centrifugal force the arms g and other pivoted limbs will be 50 swung out, all as shown by dotted lines in Fig. 1 of the drawings. Thus a child, by blowing through the pipe A, will cause the figure and the wheel to spin up and down on the standard B, and to revolve and create by its movements and the movements of its limbs 55 considerable amusement, which may be increased by the music afforded by the whistle; but such music, in many cases, may be satisfactorily dispensed with.

I claim—

1. The air-pipe A, having mouth-opening a and air-discharging opening b, in combination with standard B, and with the fan-wheel D, which is fitted loosely upon said standard to slide up and down thereon, substantially as 65 herein shown and described.

2. The toy figure E, combined with the reciprocating and rotating wheel D, fixed standard B, and air-pipe A, for operation as described.

3. The revolving and vertically-reciprocating figure E, provided with pivoted limbs g, and combined with the air-pipe A, substantially as specified.

4. The toy whistle, combined with the rotating and reciprocating toy figure, to be operated by the same air which is blown toward the whistle, substantially as specified.

CH. SCHWARTZ.
